MOTOR CONTROL SYSTEM

William F. Eames, Pittsburgh, Pa., assignor to
Westinghouse Electric & Manufacturing Com-
pany, a corporation of Pennsylvania

Application October 29, 1924. Serial No. 746,473

30 Claims. (Cl. 187—29)

My invention relates to systems of motor control and it has particular relation to such systems as are employed in connection with elevators, hoists and similar machines.

5 An object of my invention is to provide a semi-automatic control for one or more elevators in a group whereby the schedule of operation and efficiency of the system are improved.

According to my system, a person entering an 10 elevator car designates the floor number at which it is desired to stop and the car operator pushes a button or switch corresponding to that floor or landing. A number of other persons enter the car under similar conditions and, 15 when there is a sufficient load, or when a certain time interval has elapsed, the operator closes the door and actuates a button or switch to start the car. The car accelerates and travels to the next succeeding floor at which it is desired to stop. The car stops automatically and 20 after this floor has been served and the gate again closed, the elevator proceeds to the other desired floors, successively. Meanwhile, if any person at any floor desires to enter the elevator 25 he may do so by actuating a call button, whereupon the first car to arrive stops at that floor. If any car is filled or for some reason the operator does not wish to stop, he may press a non-stop button which permits the car to pass the 30 floor, in which case the next succeeding elevator car will pick up the waiting passenger. In connection with this system, means is provided for effecting accurate car stops, as hereinafter set forth.

35 My invention will be described in connection with the accompanying drawings in which

Figure 1 illustrates, diagrammatically, the mechanical arrangement of an elevator designed in accordance with my invention.

40 Fig. 2 is a diagrammatic view of the main circuits and apparatus embodying my invention.

Fig. 3 represents, diagrammatically, certain of the control circuits employed in connection with the system of Fig. 2 and

45 Fig. 4 is a typical lay-out of push-button elevator control for serving one floor and three elevators.

In Fig. 1, a car 1a is shown as connected to a counterweight 2a by means of a cable 3a 50 running over the usual drum 4a and sheave-wheel 5a. The drum 4a is provided with a magnetic brake 6a. One hatchway wall 7a is also conventionally illustrated, together with control apparatus more fully hereinafter set forth.

55 Referring particularly to Fig. 2, I employ a

variable voltage system comprising a hoisting motor 1 having an armature 2 connected in circuit with the armature 3 of a direct-current generator 4. The generator is preferably provided with a cumulative series field-magnet 60 winding 5 and a separately excited field-winding 6, the excitation of which may be varied by means of field resistors 7 and 9. The motor 1 is provided with a separately excited field-magnet winding 11. An exciter 12 for the main machines 1 and 4 is mounted on the generator armature shaft. The generator and exciter are operated by suitable means as, for example, the illustrated induction motor 13. Relays 14 and 15 are employed as hereinafter described to 65 control the generator field excitation. Reversing switches 21, 22, 23 and 24 are provided also for controlling the generator field excitation in a familiar manner.

Referring to Fig. 3 the "up" and "down" push-buttons or switches 25 and 26, respectively, are connected for controlling the corresponding reversing or directional switches to initiate the operation of the elevator car in the desired direction. A plurality of door switches 27, of a 70 familiar character, are adapted to prevent starting the car with any door open. These switches control the operating coil of a relay 28 for the purpose stated. This relay, however, permits movement of the elevator at slow speed 75 within prescribed limits at any floor, in accordance with the operation of the floor-landing switches 29 and 30. These switches are rendered inoperative normally by means of retiring magnets or coils 31, illustrated in Figs. 1 and 2, 80 and which are energized when the elevator is operating at high speed. The switches 29 and 30 are retired bodily so that normally they will not engage operating cams located in the hatchway. The retiring magnets are energized by relay 32 upon the closure of the door switches 27 85 to effect the energization of the operating coil of relay 32. Switches 29 and 30 are initially in their illustrated positions when the "up" direction coils 21 and 23 are first energized. When the car is substantially at rest adjacent to any landing, the switches 29 and 30 will be released by the opening of stop switches 33, which de-energize relay 32, and will engage an operating 90 cam 35 that is located in the hatchway as illustrated in Fig. 1.

The operation of the elevator is effected by means of up and down relays 36 and 37 that are adapted to be self-holding. That is to say, relay 100

36 is closed by means of an operating coil 38 and remains in that position until released by a coil 39 that is adapted to actuate the relay to open position. Similarly, the down relay 37 is closed by means of coil 40 and opened by means of coil 41. At each floor there is provided a slow-down relay 42 for each car comprising an operating magnet having a portion 43 of its magnetic circuit mounted in the hatchway and another portion 44 carried by the elevator car. A switch or relay of similar character is described in the copending application of Ray P. Higbee, Serial No. 551,483, filed April 11, 1922, which has matured into a Patent No. 1,561,232, November 10, 1925, and assigned to the Westinghouse Electric and Manufacturing Company and in the copending application of John F. Clancy, Serial No. 559,997, filed May 11, 1922. Such a relay becomes operative only when the car is adjacent thereto, whereby the magnetic circuit is completed and the operating coil 45 becomes effective to actuate the relay. One of the relays 33 for stopping the cars is provided at each landing for each car. These relays are preferably of the same type as the slow-down relays 42. By this means, effective control is provided for the elevator without the noise incident to mechanical engagement of cam-operated switches.

30 Referring to Fig. 4, push-buttons or switches 46 and 47 are mounted at each landing to control the stopping of an approaching car. These switches respectively operate the relays 48 and 49 to set up circuits for the corresponding slow-down and stop relays. For each car-floor in each elevator car there is a push-button switch 51, 52 or 53 for controlling suitable transfer-type relays 54, 55 or 56 respectively, whereby the car operator may cause the car to stop at the 40 desired floor or floors at which passengers on the car desire to leave the car.

45 My invention will be best understood from the following description of operation: Assuming the elevator to be at the first or main floor, its upward movement is effected by the operation of switch 25, whereby reversing switches 21 and 23 are closed to energize the generator field winding 6. Simultaneously therewith, relay 36 is closed and remains closed after switch 25 is released. Relay 28 is energized through the circuit of the door switches 27, but the holding circuit through interlock "21-in" and landing switch 29 maintains the direction switches in their operative positions. The elevator is therefore accelerated by the closure of field accelerating relay 15 which excludes generator field resistor 7.

60 Relay 15 is controlled by relay 14, the operating coil of which is in circuit with the door switches 27, so that upon closure of the door switch circuit, relay 14 is picked up and in turn energizes accelerating relay 15. It will be noted that the operating coil of relay 14 is also controlled by the slow-down relays 42, which are normally closed but become effective to control the generator field excitation and slow down the motor, as hereinafter described.

70 The car travels upward until one of the slow-down relays 42 becomes effective in a manner to be hereinafter described. This relay releases relay 58, which connects resistor 9 in shunt relation to the generator field-winding 6. Continued movement of the elevator effects the opening of the stop relay 33, which de-energizes re-

lay 32, thereby interrupting the circuit of the retiring coils 31 of the landing switches.

80 The magnet cam or armature 44 is of suitable length to maintain the slow-down and stop relays in their inoperative positions in bringing the car to the landing position. Under the present circumstances the switches would be arranged to stop the car slightly short of the landing, but, before actually stopping, the levelling switches 29 would be effective to continue the 85 car movement to the exact landing position without interrupting the motor circuit. It is obvious, however, that suitable positioning of relays 43 and 33 and proper regulation of the motor will permit the car to stop level with the floor without the use of the levelling device. In accordance with my invention, if the cumulative generator series-field winding 5 is suitably designed, the motor speed characteristic will be substantially independent of car-load, so that accurate stops may be effected independently of load conditions. In such cases the levelling switches 29 and 30 are not necessary, since it is possible to effect automatic landing by the use of the herein described slow-down and stop relays 42 and 33 which may be adjusted to stop the car at any desired point. I have found that through the use of a generator having proper field characteristics, the car will always stop accurately with respect to the landing. Where extreme accuracy is required, it may be desirable to provide the additional levelling features.

90 In the illustrated system, if the car tends to stop below the landing, it will be brought to the landing when the door switch 27 is opened, thereby-releasing relay 28, the lower member of which establishes an automatic landing or leveling circuit comprising reversing switches 21 and 23 and switches 29 and 30, which are now in their lower closed positions and controlled by the levelling cam 35. If the car stops above the floor, switches 29 and 30 assume their upper closed positions to complete a circuit through the upper contact members of relay 28 and energize the down reversing switches 22 and 24. This 105 general method of levelling, or effecting an automatic landing, is familiar to those skilled in the art, but certain additional novel features will appear from a further description of my invention.

110 In order to insure the generation of sufficient voltage to lift heavy loads at slow speed, a series relay 59 of a well-known type is provided for shunting a portion of resistor 7.

115 Further details of automatic control are illustrated in Figure 4. If the operator's push button 51 in the car is closed, transfer relay 54 is energized and holds itself closed through interlock 62. This relay is provided with upper contact members 63 that connect all the slow-down and stop relay coils 45, 64, 65 and 66 of the corresponding elevator in circuit. When the car approaches any floor from either direction of travel, the armature member carried by the car arriving adjacent the slow down relay for the direction in which the car is moving, completes 140 the magnetic circuit previously referred to and effects the energization of the proper slow-down switch 42 (Fig. 3). The armature member 44 then becomes effective to actuate the stop relay 33. Opening the door closes door switch 67 and 145 effects the operation of a relay 68 to interrupt the holding circuit of the transfer relay 54, and the car is then ready to start again in the same direction when the door is again closed. Assuming that the up relay 36 is still closed, the car 150

will continue its upward movement. Relay 71 is held closed by relay 36 and if a waiting passenger actuates the up floor button 46, the operating coil 72 effects the closure of relay 48, thereby completing a circuit through relays 48, 71 and 74, the lower contact members 75 of relay 54 and the slow-down and stop relay coils 45, 64, 65 and 66. When the car approaches the floor, it will automatically stop to take on the waiting 10 passenger, unless the car operator actuates the non-stop switch 76, which actuates relay 74 to interrupt the above traced slow-down and stop circuit and allows the car to continue its movement. In the latter event, if elevator #2 is the 15 next to approach the landing it will be automatically stopped, since a slow-down and stop circuit is completed through relays 48, 81, 84 and 55 to energize the slow down and stop coils 85 to 88, inclusive, which control #2 elevator in 20 the same manner that #1 elevator was controlled.

Fig. 4 illustrates the typical connections corresponding to any single landing that is to be served in a system comprising three elevators. 25 Similar connections are provided for each landing to be served and, therefore, it is considered unnecessary to duplicate these connections for a plurality of landings. The up and down buttons 46 and 47 at each landing control all the elevators through relays 48 and 49.

When any car stops at a landing in response to a call from that floor or in response to the car operator's switch for that floor, the 35 circuits that have previously been set up to stop the other cars at this landing are rendered ineffective, or as commonly expressed, the "calls" governing said other cars are automatically "cancelled". In accordance with my system such control is effected by means of a plurality 40 of relays 68 that are controlled by means of auxiliary door switches 67, which are normally open. When any car stops at the desired landing, the opening of the landing door closes the corresponding door switch 67 to energize the operating coil of the relay 68, which establishes a 45 circuit for the retrieving coil 90 to effect the opening of relay 48; thus governing all cars traveling in the up direction and resetting relays 54, 55 and 56. This operation does not effect the 50 control of cars traveling in the down direction. These cars are under the control of relays 91, 92 and 93, which are in circuit with the retrieving coil 94 for opening relay 49. This arrangement becomes necessary in order that there 55 will be no interference with the operation of cars traveling in the opposite direction to those intended to be stopped. It is my intention that all the elevators starting in a given direction will continue to the end of the car travel as previously set forth, and likewise cars coming in 60 the opposite direction respond to calls of passengers desiring to travel in that direction. Such an arrangement is adapted to establish the most economical and efficient service schedule.

65 It is believed that the effectiveness and utility of my system will be apparent to those skilled in the art and that modifications may readily be made therein without departing from the spirit and scope of my invention.

70 I claim as my invention:

1. In an elevator system, the combination with a car and controlling means therefor comprising an up and a down switch in the car, of a call switch at each landing, a plurality of relays for each landing responsive to the call switch for

controlling said car, and an armature member carried by said car for rendering said relays effective.

2. In an elevator system, the combination with a car and controlling means therefor, of a call switch at each landing, a plurality of relays for each landing responsive to the call switch for controlling said car, and an armature member carried by said car for rendering said relays effective. 80

3. In an elevator system, the combination with a car and controlling means therefor, of a call switch, a plurality of relays responsive to the call switch for controlling said car, and an armature member carried by said car for rendering said relays effective. 85

4. In an elevator system, the combination with a car and controlling means therefor comprising an up and a down switch in the car, of a call switch at each landing, a plurality of relays responsive to the call switch for controlling said car, and an armature member carried by said car for rendering said relays effective. 90

5. In an elevator system, the combination with a car and controlling means therefor comprising an up and a down switch in the car, of a call switch at each landing, a plurality of relays at 100 each landing responsive to the call switch for controlling said car, and an armature member carried by said car for rendering said relays effective to slow down and stop said car. 105

6. In an elevator system, the combination with a car and controlling means therefor, of a call switch at each landing, a plurality of relays at each landing responsive to the call switch for controlling said car, and an armature member carried by said car for rendering said relays effective to slow down and stop said car. 110

7. In an elevator system, the combination with a car and controlling means therefor, of a call switch, a plurality of relays responsive to the call switch for controlling said car, and an armature member carried by said car for rendering said relays effective to slow down and stop said car. 115

8. In an elevator system, the combination with a car and controlling means therefor comprising an up and a down switch in the car, of a call switch at each landing, a plurality of relays responsive to the call switch for controlling said car, and an armature member carried by said car for rendering said relays effective to slow down and stop said car. 120

9. In an elevator system, the combination with a car and controlling means therefor comprising an up and a down switch in the car, of a call switch at each landing, and electroresponsive means partly on the car and partly in the hatchway responsive to the call switch for controlling said car. 125

10. In an elevator system, the combination with a plurality of cars and controlling means therefor comprising an up and a down switch in each car, of a call switch at each landing, a plurality of relays at each landing responsive to the call switch for controlling said cars, armature members carried by said cars for rendering said relays effective, and means carried by each car for rendering certain of said relays ineffective. 130

11. In an elevator system, the combination with a plurality of cars and controlling means therefor, of a call switch at each landing, a plurality of relays at each landing responsive to the call switch for controlling said cars, 135

- armature members carried by said cars for rendering said relays effective, and means carried by each car for rendering certain of said relays ineffective.
- 5 12. In an elevator system the combination with a plurality of cars and controlling means therefor comprising an up and a down switch in the car, of a call switch at each landing, electroresponsive means responsive to the call switch for controlling said cars, armature members carried by said cars for rendering said electroresponsive means effective, and means carried by each car for rendering certain of said relays ineffective. 80
- 10 13. In an elevator system, the combination with a plurality of cars and controlling means therefor comprising an up and a down switch in the car, of a call switch at each landing, a plurality of relays responsive to the call switch for controlling said cars, armature members carried by said cars for rendering said relays effective and means carried by each car for rendering certain of said relays ineffective. 85
- 15 14. In an elevator system, the combination with a plurality of cars and controlling means therefor comprising an up and a down switch in the car, of a call switch at each landing, a plurality of relays at each landing, responsive to the call switch for controlling said cars, armature members carried by said cars for rendering said relays effective to slow down and stop said cars and means carried by each car for rendering certain of said relays ineffective. 90
- 20 15. In an elevator system, the combination with a plurality of cars and controlling means therefor, of a call switch at each landing, a plurality of relays at each landing responsive to the call switch for controlling said cars, armature members carried by said cars for rendering said relays effective to slow down and stop said cars and means carried by each car for rendering certain of said relays ineffective. 95
- 25 16. In an elevator system, the combination with a plurality of cars and controlling means therefor comprising an up and a down switch in the car, of a call switch at each landing, a plurality of relays responsive to the call switch for controlling said car, armature members carried by said cars for rendering said relays effective to slow down and stop said cars, and means carried by each car for rendering certain of said relays ineffective. 100
- 30 17. In an elevator system, the combination with a plurality of cars and controlling means therefor comprising an up and a down switch in the car, of a call switch at each landing, electroresponsive means responsive to the call switch for controlling said car, and an armature member carried by said car for rendering said electroresponsive means effective. 105
- 35 18. In an elevator system, the combination with a car and controlling means therefor comprising an up and a down switch in the car, of a call switch at each landing, electroresponsive means responsive to the call switch for controlling said car, and an armature member carried by said car for rendering said electroresponsive means effective. 110
- 40 19. In an elevator system, the combination with a car and controlling means therefor, of a call switch at each landing, electroresponsive means responsive to the call switch for controlling said car, and an armature member carried by said car for rendering said electroresponsive means effective to slow down and stop said car. 115
- 45 20. In an elevator system, the combination with a plurality of cars and controlling means therefor comprising an up and a down switch in the car, of a call switch at each landing, electroresponsive means partly on the car and partly in the hatchway responsive to the call switch for controlling said car. 120
- 50 21. In an elevator system the combination with a plurality of cars and controlling means therefor, of a call switch at each landing, relays responsive to the call switch for controlling said cars, armature members carried by said cars for rendering said relays effective, and means carried by each car for rendering certain of said relays ineffective. 125
- 55 22. In an elevator system, the combination with a plurality of cars and controlling means therefor comprising an up and a down switch in the car, of a call switch at each landing, relays responsive to the call switch for controlling said cars, armature members carried by said cars for rendering said relays effective to slow down and stop said cars, and means carried by each car for rendering certain of said relays ineffective. 130
- 60 23. In an elevator system, the combination with a car and controlling means therefor, of a call switch at each landing, and electroresponsive means partly on the car and partly in the hatchway responsive to the call switch for controlling said car. 135
- 65 24. In an elevator system, the combination with a car and controlling means therefor comprising an up and a down switch in the car, of a call switch at each landing, and electroresponsive means partly on the car and partly in the hatchway and means responsive to the call switch for rendering said electroresponsive means effective to slow down and stop said car. 140
- 70 25. In an elevator system, the combination with a car and controlling means therefor, of a call switch at each landing, and electroresponsive means partly on the car and partly in the hatchway and means responsive to the call switch for rendering said electroresponsive means effective to slow down and stop said car. 145
- 75 26. In an elevator system, the combination with a plurality of cars and controlling means therefor comprising an up and down switch in each car, of a call switch at each landing, electroresponsive means partly on the car and partly in the hatchway responsive to the call switch for controlling said cars, and means carried by each car for rendering said car electroresponsive means ineffective to stop said car. 150

said electroresponsive means ineffective as to said car.

29. In a control system for elevators operable between a plurality of floors, a car member, a hatchway member, means for starting said car, call means for said floors, means operable responsive to said call means for stopping said car at the corresponding floor, said last-mentioned means comprising a switch, a coil normally ineffective to control said switch means on one of said members, and a magnetizable plate mounted on the other of said members for rendering said coil effective to actuate said switch when said coil and plate are adjacent.

15

30. In a control system for elevators operable between a plurality of floors, a car member, a hatchway member, means for starting said car, means for stopping said car comprising a switch and a coil normally ineffective to actuate said switch mounted on one of said members and a magnetizable plate on the other of said members for rendering said coil effective to actuate said switch when said coil and said plate are adjacent, and manually operable means at said floors for energizing said coil.
